UNITED STATES PATENT OFFICE.

EDGAR R. STODDARD, OF DETROIT, MICHIGAN.

DIE FOR FORMING SHEET-METAL VESSELS.

No. 879,922.

Specification of Letters Patent.

Patented Feb. 25, 1908.

Application filed August 8, 1907. Serial No. 387,680.

To all whom it may concern:

Be it known that I, EDGAR R. STODDARD, a citizen of the United States of America, residing at Detroit, in the county of Wayne 5 and State of Michigan, have invented certain new and useful Improvements in Dies for Forming Sheet-Metal Vessels, of which the following is a specification, reference being had therein to the accompanying drawings.

10 In forming sheet metal bodies with inclined or flaring sides by means of drawing dies one or both of whose coacting members is necessarily variable, it is necessary that a constant pressure be exerted upon the blanks by the 15 surfaces of the dies during the operation, to prevent corrugation or buckling of the metal.

This invention relates to compound drawing dies for forming sheet metal bodies with inclined walls or of variable cross-section, 20 which are adapted to exert the necessary pressure upon the blanks during the different stages of the operation to give permanence and proper form to the finished article.

The invention consists in the matters hereinafter set forth, and more particularly pointed out in the appended claims.

The particular form of die herein illustrated is adapted for forming sheet metal bath tubs.

30 Referring to the drawings, Figure 1 is a view in vertical, longitudinal section, of a die embodying the features of the invention, showing the members at the beginning of a stroke; Fig. 2 is a view in vertical cross-section on line A—A of Fig. 1; Fig. 3 is a view looking up, on line B—B of Fig. 1. Fig. 4 is a view in detail of a modified form of the die.

A female die 1 whose substantially parallel 40 wall faces 2, perpendicular end face 3 and inclined face 4 have the outer contour of a bath tub, is secured over a corresponding male die 5 which is reciprocated by a head 6 operated by fluid pressure or otherwise suitably driven in opposition to a stationary plate 7 which carries the female die, the standards 8 that support the plate affording convenient guides for the head in the form of press herein shown.

50 A horizontal clamping plate 9 through which the male die travels, secured to hydraulic plungers 10 or other suitable means, is adapted to hold the blank against the lower side 11 of the female die as the male die enters, the bottom of the upper die being

cut away and replaced by a foot plate or stripper 12 on a reciprocating plunger 13, adapted to eject the finished article.

The male die 5 consists of a suitably proportioned stationary section 14 secured on the head 6, having side walls 15 and end wall 16 corresponding to the faces 2 and 3 of the female die, and a section 17 longitudinally movable in ways 18 in the fixed member, constantly interlocked fingers 19 on the sections affording practically unbroken connections between their working faces. The movable section 17 has an inclined face 20 corresponding to the face 4 of the female die. To adapt the die to make several lengths of 70 the same article, as a bath tub, all having the same ends and width of body, the stationary section may be two-part with fixed central portion and interchangeable ends of various lengths, each adapted to be secured thereto 75 by vertical tenons 22 and cross-pins 23, suitable sizes of clamping plates and female dies being provided.

The movable section 17 has a cylindrical chamber 24 parallel to the ways 18, fitted 80 with a plunger or piston 25 whose inner end is secured to the stationary section and whose outer end has a suitable packing ring or head 26. A supply duct 27 through the piston is connected by a feed pipe 28 with suitable pressure tanks or accumulators 29, suitable swivel joints 30 being provided to permit movement of the head, a controlling valve 31 of any standard design being used to regulate the pressure. A stop-pin 32 engaging a longitudinal slot 39 limits the outward movement of the movable section.

In operation, a blank is held against the face of the female die by the clamping plate, and the opened male die brought against it; 95 the latter is then forced up. As the die enters, the perpendicular walls of the vessel are turned up in the usual manner. The inclined face of the female die forms a cam surface 100 down which the corresponding edge of the movable die section rides over the interposed blank, the pressure of the fluid in the cylinder being regulated so that the metal is drawn smoothly and held against springing until the final registration of the dies gives a permanent set to that portion of the metal constituting the sloping side of the tub. The male die is then retracted through the clamping plate, the foot plate following it as an ejector that holds the blank on the receding die. 110

As the sides of the dies do not exert appreciable lateral pressure, the metal between them is not permanently set, and is liable to spring in or out when released. To obviate this the male die is expanded after withdrawal by proper manipulation of the controlling valve so that the sides of the tub are stretched taut and smooth beyond the elastic limit of the metal, thus giving them permanent shape.

It is sometimes desirable that the final impression on the bottom of the tub or article be made with a die presenting a solid continuous surface and working edge. In such case a modified form of stationary section 33 is used, with an upper face 34 and working edge 35 which corresponds with the whole bottom of the article, and a movable section 36 which slides under and is housed by the stationary member as the die is forced home, the oblique face 37 and corresponding edge 38 doing the necessary work until in register with the other section when the final pressure is exerted.

By using fluid pressure, the operator may accommodate the dies to varying thicknesses in the blank, and may also increase or decrease the pressure at different points of the stroke, as the circumstances may require.

Obviously, the details of construction and design may be varied without departing from the spirit of the invention, and I do not care to limit myself to any particular form or arrangement of parts.

What I claim as my invention is:

1. In a device for drawing sheet metal, a pair of coacting dies adapted to close past each other, one of which automatically varies to conform to the other's contour as they close, means adapted to close the dies past each other, and means to maintain pressure between the variable face of one die and the opposing face of the other in directions transverse to the die stroke adapted to act independently of the die closing means.

2. In a device for drawing sheet metal, a pair of coacting dies adapted to close past each other, one of which varies its working face and edge to conform to the other's contour as they close, means adapted to close the dies past each other and means adapted to maintain pressure between the variable face of one die and the opposing fixed face of the other die transversely to the die stroke independently of the die closing means.

3. In a device for drawing sheet metal, a pair of coacting dies adapted to close past each other, one of which varies to conform to the other's contour as they close, and means to force the variable die and interposed blank toward the other die transversely to the die stroke, and to force the variable die against the formed blank transversely to the die stroke after both have cleared the opposing die on the return stroke.

4. In a device for drawing sheet metal, a pair of coacting dies one of which is adapted to vary its working face to conform to the other's contour when the dies are closed past each other, means adapted to close the dies past each other, means adapted to force the face of the variable die against the opposing die independently of the die closing means, and means to vary the pressure exerted by said forcing means at any instant of the stroke.

5. In a device for drawing sheet metal, a pair of coacting dies one of which varies to conform to the other's contour as they close past each other, means operated by fluid under pressure adapted to close the dies past each other and means operated by fluid under pressure adapted to force the variable die toward the other die transversely to the die stroke.

6. In a device for drawing sheet metal, a pair of coacting dies, one of which varies to conform to the other's contour as they close past each other, means operated by fluid under pressure adapted to force the variable die toward the other die transversely to the die stroke, and fluid pressure controlling means.

7. In a device for drawing sheet metal, a pair of coacting dies, one of which varies to conform to the other's contour as they close past each other, means operated by fluid under pressure adapted to force the variable die toward the other die transversely to the die stroke and manually operated fluid pressure controlling means adapted to vary the pressure at any point of and during the die stroke.

8. In a device for drawing sheet metal, a pair of coacting dies, one of which consists of sections adapted to vary their relative positions transversely to the die stroke to conform to the contour of the other die as the dies close past each other, and means operated by fluid under pressure adapted to force the sections independently against the opposing die transversely to the die stroke.

9. In a device for drawing sheet metal, a pair of coacting dies, one of which consists of sections adapted to vary their relative positions transversely to the die stroke to conform to the contour of the other die as the dies close past each other, means operated by fluid under pressure adapted to force the sections independently against the opposing die transversely to the die stroke and manually operated means adapted to control and regulate the fluid pressure.

10. In a device for drawing sheet metal, a pair of coacting dies, one of which consists of sections adapted to vary their relative positions transversely to the die stroke to conform to the contour of the other die as the dies close past each other, a cylinder in one section transverse to the path of the die, a piston therein secured to an opposing section,

and means to admit fluid under pressure to said cylinder independent of the relative position of the dies.

11. In a device for drawing sheet metal, a female die, a clamping plate coacting with the female die, a male die traveling through the clamping plate, a foot plate adapted to follow the male die out through the female die and plate, said male die being adapted to vary to conform to the contour of the female die as they close past each other, and means adapted to project the variable face of the male die transversely to and independently of the die stroke.
15. 12. In a device for drawing sheet metal, a female die, a male die consisting of a fixed section and a yieldable section adapted to follow the contour of the opposing face of the female die as it enters, means to force the male die bodily into the female die and means adapted to force the sections of the male die apart transversely to and independently of the reciprocating means.
13. In a device for drawing sheet metal, a die comprising a fixed section, a second section movable thereon transversely to the die stroke, a cylindrical chamber in the movable section, a piston therein secured to the fixed section, and means to introduce fluid under pressure to said chamber.

14. In a device for drawing sheet metal, a female die having body walls substantially parallel to the die stroke and an end wall oblique to the die stroke, a male die having a fixed section adapted to coact with the body walls of the female die, and a section interlocking with the fixed section having a working edge adapted to ride on the end wall of the female die as the dies pass each other, a cylinder in one of said sections and a piston adapted to be operated by fluid under pressure and secured to the other section, coacting with the cylinder to force the movable section against the oblique end wall transversely to the die stroke.

15. In a device for drawing sheet metal provided with interchangeable female dies all having sloping end walls and similar body portions of different lengths, a male die comprising a central fixed section provided with interchangeable end portions adapted to correspond to the several body portions of the female dies, and a section movably secured

on the central section adapted to yieldingly engage the sloping end wall of any of said female dies, and means in the male die adapted to force the movable section against the sloping end wall transversely to and independently of the die stroke.

16. A machine for forming a sheet metal vessel having a substantially rectangular body portion and sloping end walls, comprising a female die having end and body walls conforming to the vessel exterior, a clamping plate adapted to hold a blank on the female die, a male die traveling through the plate adapted to vary in contour to correspond to the female die as it enters, means to force the male die through the plate and female die, means to force the clamping plate against the female die and blank as the latter is drawn in by the male die, a foot plate adapted to coact with the male die to form the bottom of the vessel and to follow said die through the female die and clamping plate on its retraction, and means to expand the male die during and after its stroke and retraction.

17. A machine for forming a sheet metal vessel having a substantially rectangular body portion and sloping end wall, comprising a female die having end and body walls conforming to the vessel exterior, a clamping plate adapted to hold a blank on the female die, a male die traveling through the plate adapted to vary in contour to correspond to the female die as it enters, means to force the male die through the plate and female die, means to force the clamping plate against the female die and blank as the latter is drawn in by the male die, a foot plate adapted to coact with the male die on the end of its instroke to form the bottom of the vessel and to follow said die through the female die and clamping plate on its retraction, means to expand the male die during and after its stroke and retraction, and a manually operated controller and regulator for the expanding means.

In testimony whereof I affix my signature in presence of two witnesses.
